UNITED STATES PATENT OFFICE.

FREDERICK W. BAUER AND JOHN C. HEILMANN, JR., OF CINCINNATI, OHIO.

CANDY-FORMING MACHINE.

SPECIFICATION forming part of Letters Patent No. 596,137, dated December 28, 1897.

Application filed February 1, 1897. Serial No. 621,457. (No model.)

To all whom it may concern:

Be it known that we, FREDERICK W. BAUER and JOHN C. HEILMANN, Jr., citizens of the United States, and residents of Cincinnati, 5 Hamilton county, State of Ohio, have invented certain new and useful Improvements in Candy-Forming Machines; and we do declare the following to be a clear, full, and exact description of the invention, such as will enable others skilled in the art to which it 10 pertains to make and use the same, attention being called to the accompanying three sheets of drawings, with the reference-numerals marked thereon, which form a part of this 15 specification.

This invention relates to machines which form substances in plastic or dough-like condition into pieces of uniform size and shape by rolling a separate piece of such mass between two surfaces, one of which is contained 20 on a molding or forming wheel, and therefore the shape of the piece is limited to such forms which may be produced by rolling—as, for instance, balls, ovoids, cylinders, ellipsoids, 25 cones, (the rolling being in this case about their major axis,) &c. One of the applications for which it is particularly well adapted is in connection with the manufacture of confectionery and bakery goods, and it is mainly 30 intended for such purpose.

This invention relates to certain features of construction and additional auxiliary adjuncts, all of which are described in the following specification and particularly pointed out 35 in the claims, together with its operation, parts, and construction, which latter is also illustrated in the accompanying three sheets of drawings, in which—

Figures 1 and 2 are side and top views of 40 the machine complete with the remote part of the track removed. Fig. 3 is an end view of the machine, showing its discharge end with the track in section. Fig. 4 in a similar view shows the end of the machine opposite 45 to the one illustrated in the previous figure. Fig. 5 shows a top view of the track and parts supported thereon. Figs. 6, 7, and 8 are sectional detail views and show the machine adjusted to form work of different shape.

In the drawings, 11 indicates the receiver, 50 substantially of cylindrical shape, which contains the dough, the same being supplied

through a hopper 12. One end of it is shaped to form a flat cone, the apex of which contains the discharge-opening 13. A screw 14 55 occupies the cylindrical body of receiver 11, being mounted at the end of a shaft 15, which is supported in bearings, one designated by 16, formed in one end of receiver 11, and the other formed in a standard 17. The rotation of this screw forces the plastic mass out through the discharge-opening, from which it issues in an unbroken body, being, however, divided at once by a rotating knife-blade 18, which at certain regular intervals passes 60 through it immediately outside of the discharge-opening. Since a fixed ratio obtains at a time between the operations of this knife and the rotation of feed-screw 14, which ratio may, however, be adjusted, it follows that the 65 cut-off pieces are all of equal size. These pieces drop at once into the forming device, which consists of two parts, complementary to each other and each containing one-half of the surface necessary to produce the particular shape. One of the halves of this forming-surface is contained in a stationary part, (indicated by 19,) while the other surface, 70 which moves past the surface first mentioned, is contained in the face of wheel 21, mounted 75 on shaft 22, whereby it is rotated and which is supported in bearings formed in standards 23 and 24. The shape to be produced in this case being a ball the surfaces are shaped accordingly, each forming a semicircular trough, of 80 which one is contained in the face of wheel 21, while the other is contained in member 19, which is closely fitted against the periphery of 85 said wheel and, starting in a horizontal plane below or in line with the discharge-opening 90 13 to bring this open end of the forming-surfaces in ready position to receive the cut-off piece, follows the wheel for about one-fourth of its circumference—that is, sufficient to bring the discharge-opening of the forming 95 device into a vertical plane, as indicated by 25. Upwardly toward the discharge-opening 13 of the receiver this member 19 spreads somewhat, assuming a shape resembling a funnel, open, however, toward the face of 100 wheel 21 and toward opening 13. This funnel-shaped part receives the pieces separated by the knife, which are gradually compressed and rolled into the shape of a ball by the ac-

tion of wheel 21, rotating in the direction of the arrow and moving its forming-surface against and past the forming-surface contained in the stationary member 19. Since 5 these two forming-surfaces have together assumed at and back of discharge-opening 25 the shape of a tube the diameter of which equals the diameter of the balls to be produced, it follows that the desired end is readily attained and the balls discharged are all of the required size.

To facilitate the rolling operation and prevent adherence of the mass to the forming-surfaces, a sprinkling device is provided, consisting of a suitable receptacle 26, having perforations in its bottom, and a rotating agitator 27 in the lower part, which causes the material used to discharge. It is so located that the material used (powdered starch or flour) 20 drops upon the forming-surface contained on wheel 21 and is therefore secured above the latter, being supported on a bracket 28, resting on and connected on top of standard 23.

The formed pieces discharged at 25 are 25 kept separated for some time to permit them to harden sufficiently to prevent sticking to each other, for which purpose they discharge upon a tray, which is so moved that the balls are deposited in rows thereonto, one dropping 30 beside the other previously-discharged one. In the drawings 29 indicates this tray, which may have grooves in its upper surface to prevent the balls from rolling away from their proper position, which keeps them separated. 35 This tray rests on a slide or sliding frame 31, which latter is again supported on a carriage 32, moving on track-rails 33 34. This carriage, with all parts supported on it, has a reciprocatory longitudinal movement in line 40 with the machine—that is, to and from the latter—which causes the balls to be deposited in rows, since the tray between each discharge has been moved a certain distance sufficient to keep the balls separated from each other. 45 At the end of each of the movements of the carriage the slide 31, resting on it, is moved laterally—that is, at right angles to the movement of the carriage—the object of this movement being to start a new row beside the previously-filled one. After a tray has been 50 filled the operation of the machine may be interrupted until an empty one has been substituted.

The formed pieces discharging from opening 25 could drop directly onto the tray, in which case, however, it would be necessary that all or at least the larger part of the carriage move under the machine-table. Since 55 this is not practicable, however, on account 60 of the support and legs of the machine-frame being in the way, the balls discharge first upon a belt 35, by which they are carried far enough out to reach the remote end of the tray when the carriage is at the end of its inward movement—that is, nearest the machine. 65 This belt is supported on a bracket-arm 36, projecting from leg 37, to which it is con-

nected, and may have flanges projecting upwardly above the edges of the belt, as shown in dotted lines in Fig. 1, to prevent the balls 70 from rolling off sidewise before reaching the outer end of the belt, where they drop off onto the tray immediately underneath. The following is a description of the mechanical means whereby all these functions are carried out:

Shaft 22, upon which wheel 21 is mounted, is rotated by a gear-train 38, actuated by a shaft 39, supported in bearings which are also formed in standards 23 and 24 and are located above the bearings for shaft 22. Shaft 39 is rotated by a bevel-wheel train 41, which is actuated by a shaft 42, supported in bearings formed in standards 43 and 17. This shaft 42 is parallel to shaft 15, which operates 85 the feed-screw, and has also mounted upon it a hub 44, which contains a short arm, affording means to secure the knife-blade 18, which latter receives thus its rotary movement. One or two of them may be used, according 90 to the size desired for the pieces supplied to the forming device, it being evident that with two knives the mass issuing from opening 13 is cut in more rapid succession, producing smaller pieces. The motion of shafts 42 and 95 15 is made dependent on each other, for which purpose they are connected by a gear-train 100 45, and one constitutes the driving-shaft for the other. If power is used, a driving-pulley of proper size may be mounted upon either 105 shaft. If hand-power is used, a crank 46 is applied either directly to shaft 42 or to an extra shaft 47, supported in bearings, one formed in standard 17 and the other in an independent standard 48. A gear-train 49 provides operative connection between these two 110 shafts 47 and 42. Gear-train 45 between shafts 42 and 15 may be arranged to permit adjustment of the speed transmitted. In this case provision is made for three speed-changes, for which purpose the gear-wheels carried on shaft 15 are loosely mounted, but may by means of a sliding key projecting through a slot in shaft 15 be locked to shaft 15, one, however, only at a time, so that shaft 115 15 is then for the time being actuated by a particular wheel and at a certain speed. This sliding key is carried by a rod 50, occupying a bore in shaft 15, the key projecting out through a slot in the latter, as stated before. 120 By means of a spring 51, the end of which engages with notches in rod 50, the latter, with the key, is held in its adjusted position. Any other suitable speed-changer and adjusting device may be used here. The agitator 27 of 125 the sprinkling device is actuated by a gear-train 52, connecting the shaft 53 of the former with shaft 39. Belt 35 is operated by a pulley 54 on shaft 55, a pulley 56 on which is rotated by a belt 57 from a pulley 58 on shaft 39. 130 59 and 61 are merely guide-pulleys for belt 35.

For purposes of reciprocating the carriage a chain 62 is used, supported on and guided

by chain-wheels 63, the bearings of which may be preferably secured to the under side of one of the track-timbers, (34 in this case.) Motion is obtained by rotating one of the 5 chain-wheels, which is done by mounting a belt-pulley 64 on the shaft of one of them, which belt-pulley is driven by means of a belt 65 from a pulley 66 on shaft 55. The connection to the carriage is by means of a pin 10 67, carried by the chain, from which it laterally projects and occupies a slot in bracket 68, secured to the carriage and projecting downwardly therefrom. The operation is readily understood. The pin as it is carried forward 15 and backward by the chain simply takes the carriage with it, moving at the turning-points up and down in the slot of bracket 68. Since delivery from belt 35 proceeds continually, it follows that for each motion of the carriage, outwardly as well as inwardly, a row 20 of balls is deposited on the tray. In order to prevent, however, the rows from being delivered on top of each other, the tray is moved laterally at each of the points where the motion 25 of the carriage reverses, the movement being sufficient to bring the filled rows away from under the delivery, advancing a clear space under the latter. This is done by shifting each time at those points the sliding 30 frame 31, upon which the tray rests, a sufficient distance sidewise, which is accomplished by the following construction:

69 are pawls pivotally supported on the inside of track-timber 33. 71 are stops engaging with that part of these pawls which is below their pivotal supports in such manner that they are capable of yielding and swinging with their upper end in one direction only. 35

72 is a disk mounted on a shaft 73, which 40 is supported in bearings 74, projecting from a timber 75, which forms a part of the carriage. A number of pins 76, circularly disposed, project from the side of the disk, all these parts being so located that the upper 45 end of pawls 69 reach within the path of the lower ones of these pins. The effect of the action when these parts engage may be seen best in Fig. 1, where the carriage coming inwardly is arriving at the end of this part of 50 its movement. A row of balls has been delivered onto the tray above, and before starting outwardly again it becomes necessary that the latter be shifted, for reasons previously mentioned. The inner pawl 69 (shown in Fig. 55 1) is therefore so located that when the carriage has moved in the lowermost one of pins 76 has also passed against and beyond the upper part of it, the pawl having yielded and dropped back again into its normal position, 60 as shown in dotted lines. In said figure the pin is shown in the act of passing over the pawl, the latter being tipped at this moment. On moving outwardly this same pin comes again in contact with the pawl, striking it from the 65 other side; but since the latter cannot yield in this direction by reason of stop 71 it follows that disk 72 must turn in order to permit its pin

to clear the pawl. This partial rotation of disk 72 also rotates its shaft 73, which rotation is transmitted to a shaft 76 by means of an interposed gear-train 77. Shaft 76 is supported in a bearing on the under side of timber 75 and has mounted upon its other end a cog-wheel 78, which rotates with shaft 76 and by meshing into a rack 79, secured to the under 75 side of sliding frame 31, shifts the latter, with the tray on top, through the required distance. Interposed rollers 81 on top of the carriage serve to reduce the friction of sliding frame 31 while so moving. Another pawl 69 is located farther out on track 33 and in such position thereon that it is also encountered by one of the pins of disk 72 at the time when carriage 32 is approaching the end of its outward movement, so that when it starts inwardly again the tray is shifted again to make room for another row of balls, which is delivered beside the row deposited previously while the carriage was moving outwardly. When the tray has been completely filled with 90 rows by its full outward movement on the carriage, the operation of the machine is interrupted until an empty tray has been substituted, after which the sliding frame is pushed back to a position shown in Fig. 3 95 and operations resumed.

In order to keep the knife-blade clean, a water-tank 82 is provided, through which it moves at every one of its rotations. Brushes 83 are provided, between which it passes after 100 having dipped into the water.

The inside of receiver 11 may be shaped to form ridges 84, which act as a means of resistance by retarding the dough, which has a tendency to move around with the rotating 105 screw instead of advancing thereon for the purpose of passing out.

In Figs. 6, 7, and 8 the capacity of the machine for producing other shapes is shown. It is done by substituting for members 19 and 110 21 other similar members, but with different forming-surfaces. The set shown in Fig. 6 forms a cylindrical piece, the one shown in Fig. 7 an ellipsoid, and the one in Fig. 8 a cone.

Having described our invention, we claim 115 as new--

1. The combination with a forming device where a plastic mass is rolled into symmetrical equal-sized pieces and which consists of a rotary member 21 having a stationary member 19 fitted against part of its periphery, the contiguous surfaces of the two being shaped to provide the forming-surfaces between which the mass is rolled, a feed device supplying the mass, a rotary knife dividing the 120 latter into equal-sized pieces before passing between the forming-surfaces, a water-tank, and brushes through which the knife passes between operations for the purpose stated.

2. The combination with a forming device 130 where a plastic mass is rolled into symmetrical equal-sized pieces and which consists of a rotary member 21 having a stationary member 19 fitted against part of its periphery, the

contiguous surfaces of the two being shaped to provide the forming - surfaces between which the mass is rolled, the lower end of member 19 forming the discharge-opening of the forming device, a removably-supported tray receiving the discharge, and mechanism operating the support of the tray in a manner to have a reciprocatory motion to and from said discharge-opening in one direction and 10 an intermittent progressive one at right angles to the direction of the other motion.

3. The combination with a forming device where a plastic mass is rolled into symmetrical equal-sized pieces and which consists of 15 a rotary member 21 having a stationary member 19 fitted against part of its periphery, the contiguous surfaces of the two being shaped to provide the forming - surfaces between which the mass is rolled, the lower end of member 19 forming the discharge-opening of the forming device, a carriage 32 having a reciprocatory motion to and from the forming device, a sliding frame 31 supported thereon, mechanism whereby the latter receives an 20 intermittent progressive motion at right angles to the motion of the carriage, such intermittent advance taking place at the terminals of the reciprocatory motion of the carriage and a tray carried by sliding frame 31 for the purpose of receiving the discharge from the forming-machine.

4. In a forming-machine, the combination of a horizontally-disposed cylindrical receiver 11, having a discharge-opening in one of its 25 ends, a feed-screw mounted therein, a forming device consisting of a wheel 21 and a stationary member 19 fitted against the periphery of the same with a space between within which the forming takes place, the receiving- 30 opening to this space being disposed below

the discharge-opening of receiver 11, a knife for severing at regular intervals the matter as it issues from receiver 11, two parallel shafts 15 and 42 one receiving motion from the other, one operating the feed-screw, the other the knife, which latter is so mounted on said shaft as to pass between the discharge and receiving openings above mentioned, a shaft 22 disposed at right angles to shaft 42 for operating the forming-wheel and intermediate connection between these two shafts for rotating shaft 22.

5. In a forming-machine, the combination of a horizontally-disposed cylindrical receiver 11, having a discharge-opening in one of its 35 ends, a feed-screw mounted therein, a forming device consisting of a wheel 21 and a stationary member 19 fitted against the periphery of the same with a space between, within which the forming takes place, a knife for 40 severing at regular intervals the matter as it issues from receiver 11, a sprinkling device with a rotary agitator mounted above wheel 21, two parallel shafts 15 and 42 one receiving motion from the other, one operating the feed- 45 screw, the other the knife, which latter is so mounted on said shaft as to pass in front of the discharge-opening above mentioned, a shaft 39 disposed at right angles to shaft 42 for operating the agitator of the sprinkling 50 device and a shaft 22 parallel to shaft 39 and driven from it upon which the forming-wheel 55 is mounted for purposes of its rotation.

In testimony whereof we hereunto affix our signatures in presence of two witnesses.
